CORE FOR TUBULAR CASTINGS

Arthur E. Troiel, Berkeley, Calif.

Application September 27, 1943, Serial No. 504,031

2 Claims. (Cl. 25—128)

The present invention relates to cores for casting tubular shapes in concrete or the like and particularly to a collapsible cylindrical core designed to be easily extracted from a long hollow tubular casting.

Long tubular concrete castings are useful as conduits for various purposes and are also used as protective and strengthening casings over wooden piles. Even where wharves are built principally of concrete piles, wood bracing piles driven at a diagonal to the vertical supporting piles are commonly used and these wood piles are jacketed with precast concrete tubular members. The present invention is ideal for forming concrete jackets for this purpose, and the invention is illustrated and described herein in such an application, although, as will be apparent from the description, it is readily adaptable to use in casting any hollow object, particularly where a cylindrical or similarly shaped core is required.

It is the object of the present invention to provide a light and durable core for making cylindrical castings having simple means for contracting its dimensions to facilitate its extraction from the casting after the casting material has set.

A further object is the provision of a cylindrical core member made up of curved metal plates with means for fixing the member at a predetermined diameter, and means for contracting its diameter without causing bulging or harmful distortion of the plates of which it is made.

Further objects and advantages of the invention are made apparent in the following specifications wherein detailed reference is made to the accompanying drawings.

In the drawings:

Fig. 1 is a transverse section through a core constructed in accordance with the present invention illustrating the core in its fully expanded position;

Fig. 2 is a similar view showing the core contracted and illustrating the same disposed within a section of a pile jacket which has been cast around it before it was constructed;

Fig. 3 is a longitudinal section taken on line III—III of Fig. 1;

Fig. 4 is an enlarged longitudinal sectional view of the jack screw nut illustrated in Fig. 3;

Fig. 5 is a similar view of a set of the pivotal fittings illustrated in Fig. 3;

Fig. 6 is a fragmentary perspective view of some of the plates which make up the body of the core illustrating a means for connecting abutting ends of the plates; and

Fig. 7 is a perspective view of a portion of a cover plate illustrating a joint between the abutting ends.

As illustrated in Fig. 1, the cylindrical core of the present invention is made up of three substantially identical arcuate sections 10, 11 and 12, and a fourth similarly shaped section 13. Each of the sections 10, 11 and 12 are provided with flanged edges 14 which project radially inwardly of the cylinder and these flanges may be joined to the flanges of adjacent sections and preferably also to reinforcing angular members shown at 15, the joining being accomplished either by bolts or rivets, not shown, or by welding. The plates 10 or 12 are off-set as indicated at 16 for reception of the edges of the plate 13 hereinafter referred to as a cover plate. One edge of the plate 13 is secured as by bolts 17 to the section 12, and the other edge overlaps the section 10, both edges being received by the off-set portions of the sections 10 and 12 in order that the outer periphery of the core will present a smooth cylindrical surface. In order to cause the plate 13 to lie snugly in position, it is preferably curved on a slightly smaller radius than the plates 10, 11 and 12. For example, if the core is 16 inches in diameter, the plates 10, 11 and 12 are curved on an 8 inch radius, while the plate 13 is given an original curve or arc on a 7 inch radius with the result that with its one edge securely fastened as by the bolts 17, its other edge will lie snugly in the recess of the plate 10, and it will assume an arc of substantially the same radius as the other three sections.

At the points of juncture of the four sections 10 to 13 are sets of links 18 which, as illustrated in Fig. 3, are connected with fittings 19 which are mounted for rotation relative to a shaft 20 which is disposed axially of the core. Each of the fittings 19 consists of an annular portion which embraces the shaft 20 (see Figs. 3, 4 and 5) and a lug 21 to which the inner ends of one of the sets of links 18 is pivoted, the outer ends of the links being pivoted, as shown, to the flanges 14. The fittings 19 are arranged in spaced groups of four, each group being retained against longitudinal movement with relation to the shaft at opposite ends of the group. Of the four fittings 19 in each group the lugs 21 on the end-most fittings are elongated as shown so that their points of pivotal connection with the rings 18 will be in the same plane as the corresponding pivotal points on the shorter lugs of the intermediate pair of fittings 19; consequently, each of

the groups of links 18 consists of four sets of links radiating from a central shaft in a common plane, with each set free to rotate relative to the shaft and relative to the other sets.

The shaft 20 may be moved longitudinally with relation to the main body of the core by means of a jack screw 23 (see Fig. 3) which has a square end 24 for the application of a suitable wrench and it operates through a nut 25 (see Fig. 4) which is braced by links 26 connected at their outer ends to the nut and at their inner ends to the flanges 14, as shown in Fig. 3. The connections of the links 26 to the nut are made through lugs 27 on collars 28, which collars embrace the nut 25. The collars are free to rotate on the nut, but are retained against longitudinal displacement by a flange 29 on one end of the nut and a screwed collar 30 at its opposite end. A set screw 31 preferably locks this collar in place. The jack screw 23 is connected to the end of the shaft 20 through the medium of a ball bearing swivel joint as shown at 32, so that upon turning of the screw the shaft 20 is moved longitudinally without being rotated. Such longitudinal movement of the shaft 20 relative to the body of the core draws the links 18 to an angular position effectively shortening the length of the links so that the body of the core formed on the plates 10 to 13 inclusive is drawn inwardly. Were all of these plates rigidly connected, inward movement of their joined edges would effect a bulging or a swelling intermediate their edges with the result that the tube would be enlarged in its diameter unless it were contracted to a point beyond the practical limits of the flexibility of the metal of which it is constructed. However, by virtue of the fact that the cover section 13 is free at one of its edges, and the fact that the links 18 are connected to the central shaft 20 through the medium of the fittings 19, each of which swivels independently on the shaft, this contracting action causes the core to assume the shape illustrated in Fig. 2 wherein all of the sections 10 to 13, though retaining substantially their normal curvature, are positioned to reduce materially the outside diameter of the core. This result is obtained by reason of the fact that the sections 10, 11 and 12 are free to contract slightly as a unit the links 18 which join them to the central shaft pivoting about the shaft to accommodate this action. The free edge of the cover section 13 assumes a position overlapping a relatively large area of the section 10. In this manner a materially reduced outside diameter is effected without imposing unusual or distorting strain on any of the parts of which the tubular shape is formed. As the links 26 which brace the jack screw nut against the core are pivotally connected to the nut, they also are free to assume the positions of the links shown in Fig. 2 upon contraction of the core.

In using the core, the jack screw 23 is turned to bring the parts to the position illustrated in Figs. 1 and 3. The core is then placed between outside form walls of any conventional construction for the formation of the concrete shape illustrated in Fig. 2, or whatever other shape may be desired, and conventional reinforcing material may be fixed between the core and the outer forms, if desired. The concrete is then poured and after it has set, the jack screw 23 is manipulated to move the shaft 20 longitudinally and through the links 18 draw the walls of the core to the positions illustrated in Fig. 2. In this condition the core may easily be extracted from the

casting without damage to either, and may quickly be set up for further use.

The description thus far assumes the plates 10 to 13 which constitute the body of the core to be made each of a single piece of metal. This would be impractical in very long cores and would be undesirable because it would definitely fix the length of each core. The invention contemplates the use of short plates joined in such a manner that the cores may be made up in various lengths and may be disassembled for convenience in transportation and storing.

A preferred means for connecting short pieces to form the plates 10, 11 and 12 is illustrated in Fig. 6 wherein abutting ends of pieces which form the plate 11 are shown as connected by a short piece 35 curved to conform to the inner surface of the plate 11 and preferably stiffened along its longitudinal edges by angle members 36 either welded to or formed integrally with the piece 35.

The piece 35 is secured to the separate portions of the plate 11 by welding or rivets 37 at one end and removably secured at the opposite end as by bolts 38. Through this construction the plates 10, 11 and 12 may be made up in any desired length and the rigidity of the whole tubular structure is maintained by staggering the joints so made at the abutting ends of the short pieces.

The cover plate 13 may be made of short pieces connected as shown in Fig. 7 by a slip joint formed of a curved member 39 secured to one of the pieces and a curved and offset member 40 secured to the other. Both of these members are provided with slots 41 along which they are welded in place. When the ends of the pieces forming the plate 13 are brought into abutment, the member 39 slips under the offset portion of the member 40 to form an interlocking but readily detachable connection.

The central shaft 20 may also be made of separable sections joined, as illustrated in Fig. 5 by a coupling 43 threaded and welded as at 44 to one of the sections and threaded to the other section to permit its removal. The coupling 43 occupies the position and performs the function of one of the collars 22 shown in Fig. 3.

The invention is herein described in a specific form for purposes of illustration but is not limited by this disclosure as it is adaptable to various changes in construction and detail, all within the scope of the appended claims.

Having thus described my invention, what I claim and desire to secure by letters patent is:

1. A contractible tubular core comprising an outer cylindrical shell, a shaft disposed axially thereof and sets of radial links connecting said shaft and shell, each set of links being connected with said shaft through fittings mounted to swivel on the shaft, said fittings being longitudinally distributed on the shaft but having pivotal connections with the links in a common plane at right angles to the shaft.

2. A contractible tubular core comprising an outer cylindrical longitudinally extended shell, a shaft disposed axially thereof throughout the entire length of the shell, sets of radial links connecting the shaft and shell at spaced intervals, each of said sets of links being connected with said shaft through a plurality of fittings mounted to swivel independently on the shaft, the fittings for each set of links being longitudinally distributed on the shaft and having lugs extending into a common plane, and pivotal connections between said lugs and the links arranged in said common plane at right angles to the shaft.
